Patented Nov. 23, 1915.

COLUMBIA PLANOGRAPH CO., WASHINGTON, D. C.

UNITED STATES PATENT OFFICE.

CHARLES H. BARNES, OF ILION, NEW YORK, ASSIGNOR TO REMINGTON ARMS & AMMUNITION COMPANY, OF ILION, NEW YORK, A CORPORATION OF NEW YORK.

GUN-SIGHT.

1,161,280.

Specification of Letters Patent. Patented Nov. 23, 1915.

Application filed January 9, 1913. Serial No. 740,991.

To all whom it may concern:

Be it known that I, CHARLES H. BARNES, of Ilion, in the county of Herkimer and State of New York, have invented a certain new and useful Gun-Sight, of which the following is a specification.

This invention has for its object the production of a gun sight and especially a sight of the class known as peep or rear aperture sights, which is particularly simple and economical in construction and highly efficient in use; and the invention consists in the combinations and constructions hereinafter set forth and claimed.

In describing this invention reference is had to the accompanying drawings in which like characters designate corresponding parts in all the views.

Figure 1 is a side elevation of my gun sight. Fig. 2 is a rear elevation thereof. Figs. 3 and 4 are longitudinal sectional views on line "A—A", and "B—B", Figs. 1 and 2, respectively. Fig. 5 is a fragmentary view illustrating the parts shown at the lower end of Fig. 3, and especially the action of the detent and its spring during pivotal movement of the sight. Figs. 6, 6^A, 6^B are detail views of the detent. Figs. 7 and 7^A are, respectively, a plan and a side elevation of the sleeve. Fig. 8 is a side elevation of the body member.

1 is the base which is shaped to be secured to the receiver of the gun, the same being adapted to be secured in position by screws 35 2. In the illustrated form of my invention, the base is formed with a pair of upwardly extending lugs 3 and with a concave under surface 4 designed to fit upon the upper face of the receiver of the gun.

40 5 is the body or hinge member or piece extending between the lugs 3 and hinged thereto, the body member having a cylindrical portion formed with a radially extending boss 6 on one side thereof. Said member 5 is also formed with a socket 7 extending radially thereinto across the axis thereof, the socket opening through the boss 6 and being arranged coaxially therewith.

50 8 is a hinge pin or screw extending transversely through the lugs 3 and hinge or body member 5 and the socket 7 therein, and tending to clamp the lugs on the sides of the body member 5.

9 is a sleeve extending into the socket 7 55 of the body member 5 and having a trans-

verse opening 10 therethrough for receiving the hinge pin 8, the sleeve extending above the body member and being formed with an annular shoulder 11 preferably located at its upper end, and with a lengthwise slot 12.

13 is a sight member having a head at its upper end formed with the sight aperture 14. The member 13 also comprises a stem 15 fitting within the sleeve 9 and having a lengthwise tongue 16, Fig. 4, having threads at its outer end or edge.

17 is a nut encircling the sleeve and having its threads arranged to engage the threads of the tongue 16, the nut being held from endwise movement, it engaging at its upper end with the shoulder 11 of the sleeve and being held against said shoulder by a spring 18 which takes up any looseness in the threads. Hence accuracy in the adjustment of the sight member 13 is insured. As shown the spring 18 consists of a spring washer encircling the sleeve and interposed between the lower end of the nut 17 and the upper or outer end of the boss 6 of the body member 5. The sleeve 9 is held from turning with the nut by the hinge pin and hence proper relation between the aperture 14 and the base is preserved so that said aperture will always coincide with the aiming alinement. Obviously during the turning of the nut, the sight member 13 will be raised or lowered. If desired, to enable the sight to be readily adjusted for different ranges of shooting, the nut may be formed with a scale 19 at its upper end, Figs. 1 and 2, coacting with a fixed point on the collar, the graduations of the scale corresponding to sub-divisions of the thread of the nut so that the height to which the sight member 13 will be raised upon the turning of the nut in the proper direction, can be determined by the scale. This nut with its scale forms practically micrometer adjustment. The nut is also formed with a corrugated periphery as shown at 20.

When the rifle is not in use, the peep sight is swung on its pivot until it lies alongside the contiguous portion of the gun and when in use it is swung into an upright position.

105 The movable part of my gun sight is held in its upright position by means of a spring pressed detent 21 movable through a guide opening 22 in one of the lugs 3 and having a tooth 23 coacting with a notch 24 formed

in one side face of the body member 5, Fig. 8, which comes into registration with said detent when the body member and parts carried thereby reach the upright position, the 5 tooth 23 and notch 24 being so shaped, that is, having complementary inclined sides, that the tooth will ratchet out of the notch, Fig. 5.

The detent is here shown as a cylindrical plunger having its tooth 23, Fig. 6, extending diametrically at one end thereof for co-acting with the notch 24, the detent also having an eccentric pin 25 at its other end and also a rounding surface 26 above the eccentric pin. This detent is pressed into 10 operative position by means of a sheet metal spring 27 bearing at one end at 28 against the outer side face of one of the lugs 3 and at its other end against the outer face of the plunger, it being provided with a perforation for receiving the eccentric pin 25.

The intermediate part of the spring is formed with an elongated slot through which the hinge pin 8 extends and the spring is held under tension by the head 29 of the 25 hinge pin. In order to prevent undue tensioning of the spring, said pin 8 is also formed with a shoulder 30 contiguous to the head 29, the shoulder being arranged to engage the outer face of one lug 3 and thus 30 limit inward movement of the hinge pin.

This gun sight is particularly advantageous in that it is particularly simple in construction, economical in manufacture, highly efficient, accurate and durable in use.

35 What I claim is:

1. A gun sight comprising a base, a member pivotally mounted therein and provided with a radial socket, a sleeve having an integral shoulder at one end and its other end 40 held in said socket, a nut retained between said shoulder and said member and provided with an internal thread, and a sight member having a stem guided in the sleeve and a part coöperating with the threaded part of 45 the nut, substantially as and for the purpose described.

2. A gun sight comprising a base, a sleeve mounted on the base, and formed with a lengthwise slot, a sight member having a 50 stem extending into the sleeve, and a tongue extending through the slot and having threads, an adjusting nut encircling the sleeve and coacting with said threads, and being held from endwise movement, means 55 for holding the sleeve from turning, and a pin extending transversely through the base and the sleeve for hinging the sleeve to the base and also holding the sleeve from turning about its lengthwise axis, substantially 60 as and for the purpose set forth.

3. A gun sight comprising a base, a body member hinged to the base, a sleeve extending into the body member, a hinge pin extending transversely through the sleeve, body member and the base, and a sight mem-

ber extending into the sleeve, substantially as and for the purpose described.

4. A gun sight comprising a base including a pair of lugs spaced apart, a body member extending between the lugs and being 70 formed with a socket, a sleeve extending into the socket, a hinge pin extending transversely through the lugs, the body member and the sleeve, a sight member extending into the sleeve, and means for elevating and lowering 75 the sight member, substantially as and for the purpose specified.

5. A gun sight comprising a base, a member hinged to the base, and formed with a 80 socket, a sleeve extending into the socket, a hinge pin extending transversely through the base, said member and the sleeve, the sleeve being formed with an annular shoulder and with a lengthwise slot, a sight member having a stem slidably fitting within the 85 sleeve, and a tongue extending through the slot of the sleeve and provided with threads, a nut turning on the sleeve and having a thread for coacting with the threads of said tongue, and a spring interposed between the 90 nut and the hinged member for holding the nut engaged with said shoulder and taking up any looseness in the threads, substantially as and for the purpose set forth.

6. A gun sight comprising a base, a member hinged to the base and formed with a 95 socket, a sleeve extending into the socket, a hinge pin extending transversely through the base, said member and the sleeve, the sleeve being formed with an annular shoulder and with a lengthwise slot, a nut turning on the sleeve, a sight member having a 100 stem slidably fitting within the sleeve, and a tongue extending through the slot of the sleeve and having threads for coacting with the threads of said nut, a spring interposed between the nut and the hinged member for holding the nut engaged with said shoulder, and taking up any looseness in the threads, 105 and a spring pressed detent coacting with the hinged member, substantially as and for the purpose described.

7. A gun sight comprising a base, a member hinged to the base, and a spring-pressed 110 ratcheting detent movable in the base and in a direction parallel to the axis on which said member turns and coacting with one side of said member, substantially as and for the purpose specified.

8. A gun sight comprising a base formed 115 with a transverse guide, a member hinged to the base, a pin hinging said member to the base and having a head at one end, the pin extending through said member and the base, a detent movable in the guide in the 120 base and being arranged to coact with said member, a spring carried by the base and coacting with the detent and with the base and having a portion interposed between the head of the hinge pin and the base whereby 125 130

the spring is held under tension by said head, substantially as and for the purpose set forth.

9. A gun sight comprising a base formed with a guide, a member hinged to the base, and a detent for coacting with said member and holding the same in its adjusted position about its axis, the detent including a cylindrical plug slidable in the guide of the base, and having a tooth at one end, and a sheet metal spring for moving the detent in one direction, the spring coacting with the detent and being connected to the other end of the detent eccentric to the axis thereof, substantially as and for the purpose described.

10. A gun sight comprising a base formed with a transverse guide, a member hinged to the base, a pin hinging said member to the base comprising a screw extending through the base and said member and threading at one end into the base and having a shoulder at its other end, for limiting the movement of the screw inwardly, and a head at the outer side of the shoulder, a detent for holding said member in its adjusted position, the detent being movable in the guide, and a sheet metal spring bearing at one end against the base and at its other end against the detent, and the intermediate portion thereof being formed with a slot for receiving said shoulder and being engaged and held under tension by the head of the screw, substantially as and for the purpose specified.

11. A gun sight comprising a base having a pair of upwardly extending lugs, a member extending between the lugs, and engaging opposing faces of the same, a hinge pin extending through the lugs and said member, one of the lugs being formed with a transverse guide, a detent slidable in the guide and coacting with said member, and a spring bearing at one end against the outer face of the lug formed with the guide, and

its other end bearing against said detent, the intermediate portion thereof being arranged to engage the hinge pin and held under tension thereby, substantially as and for the purpose set forth.

50

12. A gun sight formed with a pair of lugs spaced apart, a body member extending between the lugs and engaging the same, the body member being formed with a socket, a sleeve extending into the socket, a hinge pin extending through said lugs, the sleeve and the body member and threading at one end into one of the lugs, and having a shoulder at its other end for engaging the outer face of the other lug and also having a head at the outer end of the shoulder, the latter lug being formed with a guide opening extending therethrough, a detent movable in the guide into and out of engagement with the body member, a spring acting on the detent and bearing at one end against the body and at its other end against the detent, and being formed intermediate of its ends with a slot for receiving said shoulder, the spring being held under tension by the head of the hinge pin, the sleeve being formed with a lengthwise slot and an annular shoulder, a sight member having a slot fitting the sleeve and a tongue extending through the slot and having threads at its outer end, a nut turning on the sleeve and having its threads coacting with the threads of the tongue, and a spring washer interposed between the body member and the nut, said washer encircling the sleeve, substantially as and for the purpose described.

55

In testimony whereof, I have hereunto signed my name in the presence of two attesting witnesses, at Ilion, in the county of Herkimer, in the State of New York, this 11th day of December 1912.

60
